UNITED STATES PATENT OFFICE.

ROBERT STALLMEIER, OF ROCHESTER, NEW YORK.

SASH-PULLEY.

SPECIFICATION forming part of Letters Patent No. 673,931, dated May 14, 1901.

Application filed August 3, 1900. Serial No. 25,803. (No model.)

To all whom it may concern:

Be it known that I, ROBERT STALLMEIER, a citizen of the United States, residing at Rochester, in the county of Monroe and State 5 of New York, have invented a new and useful Pulley, of which the following is a specification.

My invention relates to pulleys, and more particularly to that class of pulleys used in window-frames for supporting the sash-weight; and it has for its object to produce a pulley of this kind and a frame or casing for the same which will be simple, compact, and efficient and which can be quickly secured 15 in position without the use of screws or other separate retaining devices.

With this object in view my invention consists in the improved construction and novel arrangement of parts of a pulley and a casing 20 therefor, as will be hereinafter more fully set forth.

In the accompanying drawings, in which the same reference-numerals indicate corresponding parts in each of the views in which 25 they occur, Figure 1 is a perspective view of a pulley and its casing embodying my invention. Fig. 2 is a front elevation, partly in section, of the same. Fig. 3 is a sectional view of the pulley and its axle. Fig. 4 is a 30 view of the blank from which the frame or casing is made, and Fig. 5 is a top view of the casing complete.

Referring more particularly to the drawings, 1 indicates the pulley, which is preferably made from two annular disks 2 and 3, each 35 of which is curved or flared outwardly at its rim or periphery, as shown at 4, and bulged outward near its inner edge, as shown at 5. The flat portions 6 of the two disks between 40 the bulge and the curve are secured together in any desired manner, as by the rivets 7. An annular ring or washer 8 is riveted or otherwise secured between the inner edges 45 of the two disks within the bulged portions. The inner portion of each of the bulges, adjacent to the ring, is formed or provided with a seat 9 for the reception of antifriction ball-bearings 10, the outer edge of the seat extending over the balls far enough to retain them 50 in their positions.

A pin 11 is passed through the perforation or opening formed through the center of the

pulley and has its ends flattened or otherwise secured in engagement with the sides of the frame 12. The frame is preferably formed 55 from a single piece of material 13, the ends of which are provided with lips or extensions 14, adapted to be bent laterally for engaging with the window-sash, and the central portion of each edge is notched or cut away, as 60 shown at 15. The portion of each edge between the notch 15 and the end of the blank 13 is preferably provided with a lip 16, which is adapted to be bent outward for engaging 65 with the window-casing to hold the frame in position therein. Extending from the notch at a distance from the outer edge nearly to each end of the blank is an outwardly-bulged portion 17, which is adapted to engage with the 70 sides of the opening in the casing and assist in retaining the frame in position, there being four of these outwardly-bulged portions. The blank is provided with two openings 18, which register with each other when the blank is folded and form receptacles for the heads of the rivets, the portion of the frame surrounding the opening being slightly countersunk, as shown at 19. The central portion of the blank, between the two notches, is adapted to be bent or curved at a distance into a loop 20 when 75 the sides of the frames are bent parallel with each other, and the edges of the frame, at the ends of the lips 16, are curved inward, as shown at 21, so as to abut against each other when the frame is complete.

In using my improved pulley and frame as above described the pulley is first formed by securing its disks together and inserting the rivet and ball-bearings through its center. The blank is then doubled upon itself to cause 90 its ends to overlap the sides of the pulley and permit of the passage of the ends of the rivets through the openings therein. The heads of the rivets are then fastened to the sides, which completes the structure.

Openings are made in the sides of the casing at the top in the usual manner for the insertion of the frame and pulley, the openings being of substantially the same area as the pulley-frame in longitudinal section. The 100 frame is then inserted into the opening as far as it will go, the lips 14 engaging with the front wall of the casing and limiting the further inward movement of the frame and pre-

senting a neat appearance. A suitable instrument of any kind is then inserted between the top and bottom, respectively, of the pulley and the frame, and the lips 16 are bent 5 outward and forced into the wood of the frame a sufficient distance to engage therewith and prevent the removal of the frame from the casing. The cord from the window can then be passed over the pulley between the top of 10 the frame and the loop 20 at the rear and down to the weight.

As above described, it will be seen that my improved pulley and frame can be manufactured very cheaply, as the disks forming the 15 pulley can be stamped out of sheet metal and rigidly secured together at their flat portions, which will form the web or central portion of the pulley, and the frame can be formed from a single piece of sheet metal stamped into 20 shape with suitable dies and bent at its central portion, so that its sides may be rigidly secured in position by means of the rivet upon which the pulley is supported. The frame is invertible, so that it can be used upon either 25 side of the window-casing, and is complete within itself, not requiring extra retaining means, and will be rigidly held in place after having been once put in position.

Having thus fully described my invention, 30 what I claim as new, and desire to secure by Letters Patent, is—

1. As a new article of manufacture, a pulley formed from two annular disks, the edge of each of which is curved outward and the 35 portion adjacent to the inner edge is bulged outward and provided with a seat for ball-

bearings, and an annular collar secured between the flat inner edges of the disks, substantially as described.

2. In a pulley, the combination, with two 40 annular disks having their outer edges flared outward to form a groove and bulged outward near their inner edges to form ball-bearing seats, a frame having its edges in contact above and below the pulley and its sides perforated to register with the opening through the pulley, a rivet through the pulley and in engagement with the sides of the frame to hold said edges in contact, and ball-bearings 45 in the seats of the pulley in engagement with 50 said rivet, substantially as described.

3. In a pulley, the combination, with a frame formed from a single piece of material, the central portion of which is cut away on its edges and doubled upon itself and the ends 55 are perforated and provided with laterally-bent lips at their forward edges and having their edges above and below the pulley bent toward and in contact with each other, said upper and lower bent portions being provided 60 with lips that are adapted to be bent outward to engage with the support for the frame and hold the pulley-frame in position, a rivet through the perforations in the ends to hold the ends of the frame in position, and a pulley 65 journaled upon said rivet, substantially as described.
